DOOR HINGE

Martin J. Goulooze, Grand Rapids, Mich., assignor to Nash-Kelvinator Corporation, Detroit, Mich., a corporation of Maryland

Application May 7, 1947, Serial No. 746,543

4 Claims. (Cl. 16—128)

1

This invention relates generally to refrigerator cabinets and more particularly to door hinges therefor.

It is an object of the present invention to provide a refrigerator door hinge leaf of a character such that screws for attaching the hinge are hidden from view.

Another object of the invention is to provide an improved refrigerator door hinge leaf which may be of reduced width with corresponding saving in material without affecting the efficiency of the hinge.

A further object of the invention is to provide an improved refrigerator door hinge leaf of a character to reinforce the door structurally.

Further objects and advantages of the present invention will be apparent from the following description, reference being had to the accompanying drawings, wherein a preferred form of the present invention is clearly shown.

In the drawings:

Fig. 1 is a front view of a refrigerator cabinet embodying features of the present invention;

Fig. 2 is a fragmentary, enlarged sectional view of the cabinet, taken along the line 2—2 of Figure 1;

Fig. 3 is a vertical sectional view of the cabinet, taken along the line 3—3 of Figure 2;

Fig. 4 is a perspective view of a part of my door hinge;

Fig. 5 is a perspective view of a part of the cabinet;

Fig. 6 is an enlarged, fragmentary view of the refrigerator cabinet at one of the door hinges;

Fig. 7 is a cross sectional view of the refrigerator cabinet, taken along the line 7—7 of Figure 6, and

Fig. 8 is a vertical sectional view of one of the door hinges, taken along the line 8—8 of Figure 7.

Referring to the drawings by characters of reference, the numeral 20 designates generally, a refrigerator cabinet having a storage compartment closed at the front thereof by an access door 22. The access door 22 is hinged to one side of the cabinet proper 20 by my improved hinges, designated generally by the numeral 26, there being three of these hinges in the present instance.

The cabinet 20 comprises an outer metal casing 28 and an inner metal liner 30. Interposed between the outer casing 28 and the liner 30 is heat insulation 32 which may be of any suitable type. The liner 30 forms the walls of the food storage compartment. The front wall of the cabinet 20, around the compartment door

2

opening is preferably faced by trim strips or by so-called breaker strips 34 of low heat conductive material, such as a phenolic plastic material, connecting the outer casing and the liner. These breaker strips 34 are retained in channels 35 formed in the casing of the cabinet front wall. The door 22 carries a rubber sealing member 36 on the inner side thereof, arranged to engage the outer surface of the cabinet casing 28 around the door opening when the door is closed so as to seal the food storage compartment. In hanging the door 22 care must be taken that the hinges 26 are properly placed to insure that the door seal engages the cabinet outer wall surface properly around the entire periphery of the seal.

The door 22 comprises, an outer metal casing 38 and an inner facing panel 40. Insulation 42 is preferably disposed between the door casing and its inner facing panel which insulation may be of any suitable type. The door casing 38 has an inturned flange 44 around its periphery to which the facing panel 40 may be secured by screws 46 which also clamp the rubber seal 36 to the door, between the facing panel and the door casing flange 44. Preferably, the door casing flange 44 is provided with an inturned edge portion 48 to stiffen the flange.

My improved hinge 26 includes a pair of hinge leaves 50, 51 and a pintle 52. The hinge leaves 50, 51 have the usual notched, interfitting hinge ends to receive the pintle 52 for pivotally connecting the hinge leaves together. The hinge leaves 50 each have a wall abutting vertical edge 53 and a knuckle edge opposite the wall abutting edge. The leaf edge 53 is formed with an angle-like recess 55 complementary with the outer corner of the door casing 38. These hinge leaves 50 seat against the corner of the door and are held tightly thereto by screws 54 which screwthread into a nut or angle backing member 56 fitting complementary with the inner corner of the door casing 38. In hinge leaf 50, apertures for screws 54 extend through leaf edge 53 and the knuckle edge and the heads of the screws 54 are located at the knuckle edge between the hinge knuckles for ready accessibility. Further the screw heads are seated flush to avoid interference with knuckles of the other hinge leaf 51 which overlies and conceals the screwheads. As shown, the backing member 56 is wedge shape and seats against the adjacent sides of the door casing 38 adjacent the door corner. This backing member 56 reinforces the door at the corner thereof and may be welded or be other-

wise secured to the inner side and to the flange 44 of the door casing 38 or the backing member 56 may be held in place solely by the screws 54. The other hinge leaf 51 lies flat against and is attached to the outer surface of the adjacent side wall of the cabinet.

In the corner of the cabinet, adjacent the hinge leaf 51, I provide a reinforcing or locking member 58 for the outer casing 28 where the hinge leaf 51 attaches to the cabinet. This reinforcement 58 is preferably an angle member, to fit complementary with the cabinet inner corner, having one leg 60 engaging the casing inner side wall and another leg 61 engaging the casing front wall. The angle reinforcement 58 and the casing may be welded or be otherwise suitably secured together. Positioned to engage flat against the inner side of the reinforcement leg 60 is an adjustable hinge clamp 64, the clamp 64 and hinge leaf 51 being drawn together into frictional holding relation with the cabinet wall by screws 66. In the cabinet outer casing side wall and in the reinforcement leg 60 aligning clearance holes 67, 69 are provided for the screws 66 so that the clamp 64 and the hinge leaf 51 may be adjusted to proper position for best results in hanging of the door. The reinforcing angle member 58 also serves as a holder or retainer for the clamp 64. To this end, the clamp 64 is provided with notches 70 in one side edge thereof to receive tabs 71 formed out of the reinforcement leg 60, the tabs fitting loosely in the notches 70 to permit limited adjustment movement of the clamp in a vertical plane. Other tabs 72 are formed out of the reinforcement leg 61 and are bent over the clamp at the opposite side edge from the tabs 71, the tabs 71 and 72 being in vertical spaced relation as shown in Figure 5.

In hanging the door 22, the hinge leaves 50 may first be mounted on the door and rigidly secured thereto by tightening down the screws 54. The cooperating hinge leaves 51 are then attached to the side wall of the cabinet and one or more of the screws 66 of each of these hinge leaves 51 are tightened down just sufficiently to hold the hinge leaves in place. The door 22 is then positioned to interfit the hinge leaves 50, 51 and the pintles 52 are inserted pivotally connecting the leaves together. The door may now be held in closed position and adjustment of the position of the hinge leaves 51 may be made to effect proper seating of the door seal along its entire periphery against the cabinet front wall after which the screws 66 are tightened down rigidly securing the hinge leaves to the cabinet.

By reason of the large clearance holes 69 in locking member 60 and the similarly large clearance holes 67 in casing 28 to receive the screws 66, it will be seen that the positions of clamp 64 and hinge leaf 51 may be shifted some to obtain proper seating of the door seal against the face of the cabinet. When the desired position is attained, screws 66 are tightened to secure the hinges to the cabinet. In each of the present hinge leaves there are three holes for the screws 66 and a fourth hole for a locking screw 75. Using the said fourth hole as a guide, a hole is provided in the casing 28 for threaded engagement with locking screw 75 which is then tightened down and functions as a stop to prevent movement of the hinge relative to the casing 28. The screw 75 shown is of such length as to require the provision of a clearance hole therefor in clamp 64, as shown for example, more clearly in Fig. 7.

From the foregoing it will be noted that I have provided a flat-like piano type hinge which adequately supports the door in addition to the arrangement for aligning the door originally.

5 Preferably the hinged leaves are made of extruded aluminum. By utilizing a flat type hinge the overall width of the refrigerator is only slightly increased and by securing one leaf to the corner of the door the gasket seal is not disturbed and the hinge rigidly supports the door without a wide and expensive leaf on the door.

10 Although only a preferred form of the invention has been illustrated, and that form described in detail, it will be apparent to those skilled in the art that various modifications may be made therein without departing from the spirit of the invention or from the scope of the appended claims.

15 20 I claim:

1. In a door hinge for attachment to a wall corner, a hinge leaf having a V-grooved edge complementary to the wall corner and having a knuckle edge opposite the grooved edge, a plurality of spaced apertures extending through said leaf from one of said edges to the other, a plurality of screws in said apertures to secure said leaf to said wall corner and having heads flush with said knuckle edge, said screw heads being disposed between adjacent knuckles, and a knuckle edge of a second hinge leaf interfitting with said first knuckles and concealing said screw heads.

2. In a door hinge for attachment to a refrigerator cabinet having a casing, a hinge leaf to position against the outer surface of the casing, a clamping strip to position within the casing in superimposed relationship to said hinge leaf, a retainer strip interposed between said clamping strip and said casing, a plurality of apertures in said hinge leaf aligning respectively with apertures in said clamping strip and with apertures in said retainer strip, said retainer strip loosely supporting said clamping strip for movable adjustment of the latter, screws extending through said apertures and screwthreaded into said clamping strip, said retainer strip apertures and casing apertures being larger than the other apertures to allow adjustment of the position of said hinge leaf prior to tightening the screws, another aperture through said hinge leaf aligning with a clearance aperture in said retainer strip and with a smaller aperture in said casing, and a locking screw in said last-named hinge leaf aperture to screwthread into the casing to lock the hinge leaf in adjusted position.

3. In a door hinge adapted to attach a refrigerator door member to a wall member of a refrigerator cabinet, said hinge having a leaf formed with an edge to abut one of the members and a knuckle edge opposite said first edge, a pair of spaced knuckles on said knuckle edge, an aperture in said leaf extending through both of said edges, a screw in said aperture holding said leaf to said one member and having a head at said knuckle edge between the knuckles, a second hinge leaf attached to the other of said members having a knuckle edge with the knuckles thereof interfitting with the knuckles of said first leaf, and a pintle received in the interfitting knuckles of said leaves.

4. In a door hinge adapted to attach a refrigerator door member to a wall of a refrigerator cabinet, said hinge having a leaf formed with an edge to abut one of the members and a

knuckle edge opposite the first edge, a plurality of spaced knuckles on said knuckle edge, an aperture extending through said hinge leaf having one end open at said first edge and the other end open at said knuckle edge between said spaced knuckles, a plurality of screws respectively extending through said apertures to secure said leaf to said one member and having heads substantially flush with said knuckle edge, a second hinge leaf having a plurality of knuckles interfitting with said first knuckles and concealing said screw heads, and a pintle received in said interfitting knuckles pivotally connecting said leaves together.

MARTIN J. GOULOZE.
